Inventor

Frank Reese

By Clarence Walker.

His Attorney

UNITED STATES PATENT OFFICE.

FRANK REESE, OF MINNEAPOLIS, MINNESOTA, ASSIGNOR TO WATSON MANUFACTURING COMPANY, OF JAMESTOWN, NEW YORK, A CORPORATION OF NEW YORK.

CLAMP.

Application filed February 1, 1923. Serial No. 616,447.

To all whom it may concern:

Be it known that I, FRANK REESE, a citizen of the United States, residing at city of Minneapolis, in the county of Hennepin 5 and State of Minnesota, have invented certain new and useful Improvements in Clamps, of which the following, taken in connection with the accompanying drawings, is a specification.

10 This invention relates to an improvement in clamps and particularly to clamps intended for use in combination with the ventilator windows of factory sash for securing screens thereto.

15 Factory sash is generally used to designate a large frame having a plurality of panes of glass fixed therein. Such sash has in most cases one or more ventilator openings closed by hung or pivoted sashes. When

20 horizontally pivoted at the center it is obvious that the opening of the sash provides upper and lower openings and it is the purpose of this invention to provide means for securing screens in such openings.

25 Prior to this invention such screens have been secured to the factory sash by drilling holes in the framework and fastening the screen carrying clamps thereto. This method of attaching is objectionable not only 30 because it permanently mars the framework but also because it is impossible to secure the clamps in place from the inside.

The chief object of this invention is to avoid the above objections by providing a 35 clamp which can be quickly applied to the sash from the inside without marring the framework by the formation of screw holes.

40 Other objects reside in details of construction which will be set forth in the following specifications taken in connection with the drawing which forms a part thereof and in which—

Figure 1 is a front elevation of a portion 45 of a factory sash having a horizontally pivoted sash showing the screen applied to the upper opening by the use of clamps made in accordance with this invention.

Fig. 2 is a cross section through the line 2—2 of Fig. 1 showing the lower mounting 50 of the screen.

Fig. 3 is a cross section along the line 3—3 of Fig. 1 showing the mounting of the sides of the screen.

Figs. 4 and 5 show in plan and side elevation the blank from which the side clamps 55 are formed.

Figs. 6 and 7 are similar views of the side clamp blank after the forming operation has been completed.

Figs. 8 and 9 are similar views of the 60 completed side clamp.

Figs. 10 and 11 are plan and side elevations of the blank from which the bottom clamp is formed.

Figs. 12 and 13 are similar views of that 65 blank after the stamping operations have been completed.

Figs. 14 and 15 are plan and side elevations of a bottom clamp, similar to the bottom clamp shown in Fig. 2 but differing 70 therefrom in certain details of conformation.

Fig. 16 is a plan view of a blank from which the sheet metal strip, which forms one element of both types of clamps, is made. 75

Referring to the drawings, the reference numeral 20 is used to designate a factory sash having a plurality of fixed panes 21, 22, 23, 24, 25, 26, and 27 surrounding a sash 28 horizontally pivoted in the usual 80 manner at each end of the muntin 29. In the particular type shown, the upper half of the sash swings inwardly and the lower half swings outwardly. The opening of the lower half is usually protected by the use 85 of a stationary screen mounted on the inside of the vertical outlining bars and no further reference thereto will be made.

In order to screen the opening of the upper half it is necessary to allow for the 90 swinging of the sash and one way to do so is to mount the lower portion of screen upon the muntin 29 of the sash so that the movement of the sash will not interfere with the screen, as shown for example in my 95 Patent 1,343,933, dated June 22, 1920. For purposes of illustration, the clamps embodying this invention are shown applied to the screen 30 of this type which has at each side a longitudinal groove 31 into which 100 project pins 32, carried by the side shields 33 which close the side spaces between the screen and the sash. The lower edge of the screen rests upon a horizontal strip 34 which is carried by the muntin 29, as shown 105 particularly in Fig. 2. At the outer edge

- 2 of the strip 34 is formed an annular bead 35 which rests within a horizontal groove 36 of the screen corresponding to the vertical groove 31. The bead 35 is removably held in the groove 36 by means of a plurality of screws 37 which project from the inner wall of said groove into slots 38 in the annular bead 35. By the provision of these slots it is, of course, obvious that the screen 10 can oscillate vertically upon the strip 34. The horizontal strip is formed to rest upon the upper face of the muntin 29 and is provided with a plurality of slots 39 formed by striking up portions 40 from the strip. The inner 15 edge of the strip 34 is secured to the muntin 29 by clamps 41, embodying one form of this invention which pass through the slots 39 and engage the muntin 29 above or below the strip.
- 20 Referring to Figs. 10, 11, 12 and 13 this clamp is preferably made from a flat blank 42 having a hole 43 adjacent one end and a slot 44 adjacent the other end. The relative position of the hole 43 and slot 44 is indicated in Fig. 10 by dotted lines. The hole 43 may be formed first and the slot 44 formed at the time the blank is bent at right angles, as shown in Figs. 12 and 13 along a line between the slot and hole so 25 that the portion bearing the hole 43 is at right angles to the portion bearing the slot 44. After the blank has been given the form shown on Figs. 12 and 13, a plate 45, formed as shown in Fig. 16, is applied by 30 bending around the end of the clamp along the dotted lines indicated in Fig. 16. The plate may be first bent along the dotted line 46 providing a projecting portion 47 which is inserted into the slot 44 from the upper 35 side, as illustrated in Fig. 3. The portion 47 is then bent along the line 48 against the under surface of the clamp and in order to prevent the plate working loose it is bent against the outer face of the clamp along 40 the dotted line 49. In order to secure the main portion of the plate to the clamp the sides 50 are bent downwardly and inwardly around the edges of the clamp. Finally the nose 51 is bent upwardly at an acute angle 45 to the clamp, along the dotted line 52, as shown for example in Figs. 9 and 15, to provide a hook for a purpose to be described later.
- 50 Referring particularly to Fig. 2 it will be noted that the muntin 29 has a triangular-like front portion 53 and a rectangular rear portion 54 projecting from the base 55 of the front portion 53. The panes of glass 56 are embedded in putty 57 above and below the portion 54 and behind the base 55. Each clamp 41 is inserted through a slot 39 in the strip 34 and the nose 51 is forced into the putty 57 behind the upper edge of the base 55 and in front of the pane 56. Since 55 the portion of the clamp 41 bearing the hole 43 is at right angles to the slot-bearing portion, the former will lie on the lower side of the triangular front portion 53 of the muntin 29. A screw 58 in the hole 43 is tightened against the under face 59 thus 70 co-acting with the nose 51 and the line of contact between the clamp 41 and the edge of the muntin to hold the clamp in place. The slots 39 in the strip 34 are so located that when the clamps are tightened the strip 75 is securely fixed to the muntin 29. In order to increase the contacting surfaces of the strip 34 and the upper face of the muntin, it is found advantageous to give the inner edge of the strip a contour similar to the 80 muntin.
- 85 The side shields 33 are of channeled construction and are mounted upon clamps 60 which are similar in formation to the clamps 41. Referring to Figs. 4 and 5, it will be noted that the clamp 60 is formed from a blank 61 having two holes 62 and 63 formed therein. Stamped in the blank 61 are lines 64 which surround on three sides the hole 63. The blank 61, like the clamp 90 41, is bent at right angles, the portion carrying the hole 62 being at right angles to the portion carrying the slot 65 formed by the lines 64. The portion 66, defined by the lines 64, is bent back, as shown in Fig. 7, so 95 that it is at an angle of substantially forty-five (45°) degrees to the portion carrying the slot 65. The outer end of the clamp 60 has a plate 45 which is secured to this clamp 100 through the slot 65 in the same manner as pointed out above in connection with the bottom clamp 41. The vertical outlining bars 67 are of the same cross section as the muntin 29 and each clamp 61 is fixed thereon by the engagement of the nose 51 of the 105 tip 45 with the edge 68 and the engagement of a screw 69 threaded through the hole 62 with the face 70. The portions 66, when the clamps 61 are mounted upon the bar 67, lie 110 parallel to the face of the sash and to them is secured by screws 71 in the holes 63 a right angled brace 72 which carries the shield 33 in any desired manner. As a back support or guide for the screen 30 there is 115 secured to the inner face of each shield 33 a right angled strip 73 which also functions to close the space between the side edges of the screen and the shields 33.
- 120 Figs. 14 and 15 disclose a third embodiment which may be used under certain conditions in place of the bottom clamps 41. It will be observed that these clamps 74 differ from the clamps 41 merely by a provision of a rounded portion 75, as shown particularly in Fig. 15.
- 125 Throughout the specification and drawing the sash is set forth as composed of bars and muntins of a certain cross section. It is obvious that clamps made in accordance with this invention may be applied equally 130

well to bars and muntins of different cross sections so that it will be understood that I am not restricted thereby.

While certain embodiments have been shown and described, it is obvious that I am not limited thereto since other embodiments may be made without departing from the spirit and scope of this invention as set forth in the following claims.

Having thus set forth my invention, what I claim as new and for which I desire the protection of Letters Patent is:

1. A clamp, comprising two legs substantially at right angles to each other, having a transverse slot in one leg and a threaded hole in the other leg, a plate folded around the end of the first named leg and passing through the slot therein and a screw in the hole in the other leg, said plate and screw co-acting to hold said clamp in functioning position.

2. A clamp, comprising two legs substantially at right angles to each other, having a transverse slot in one leg and a threaded hole in the other leg, a plate folded around the end of the first named leg and passing through the slot therein, a screw in the hole in the other leg, said plate and screw co-acting to hold said clamp in functioning position and an article supporting portion projecting from one of said legs.

3. The combination with factory sash comprising a plurality of bars and panes mounted by putty upon said bars, of a clamp having a nose adapted to be inserted into the putty between the face of the pane and a bar upon which the pane is mounted and having means for removably engaging another portion of said bar whereby the clamp is securely mounted upon said bar.

4. The combination with factory sash comprising a plurality of bars and panes mounted by putty upon said bars, of a clamp having a nose adapted to be inserted into the putty between the face of a pane and a bar upon which the pane is mounted and a

screw threaded through said clamp into engagement with another portion of said bar whereby the clamp is securely mounted upon said bar.

50

5. The combination with factory sash comprising a plurality of bars and panes mounted by putty upon said bars, of an angled clamp, having a nose on one end which is adapted to be inserted into the putty between a pane and a bar, upon which the pane is mounted and having a screw threaded through the other leg of said clamp adapted to engage a portion of said bar so located that the bar is gripped between said nose and said screw.

55

6. The combination with factory sash comprising a plurality of bars and panes mounted by putty upon said bars, of an angled clamp, having a nose on one end which is adapted to be inserted into the putty between a pane and a bar, upon which the pane is mounted, having a screw threaded through the other leg of said clamp adapted to engage a portion of said bar so located that the bar is gripped between said nose and said screw and having a portion parallel to the face of said sash when said clamp is in position.

65

7. The combination with factory sash comprising a plurality of bars and panes mounted by putty upon said bars, of an angled clamp, having a nose on one end which is adapted to be inserted into the putty between a pane and a bar, upon which the pane is mounted, having a screw threaded through the other leg of said clamp adapted to engage a portion of said bar so located that the bar is gripped between said nose and said screw and having a portion parallel to the face of said sash when said clamp is in position and means in said portion for securing articles thereto.

70

In testimony whereof I have affixed my signature.

FRANK REESE.
